UNITED STATES PATENT OFFICE.

HORACE E. DOGGETT, OF PHILADELPHIA, PENNSYLVANIA, ASSIGNOR OF ONE-HALF TO E. M. COOPER, OF SAME PLACE.

STEAM-MOTOR.

SPECIFICATION forming part of Letters Patent No. 364,225, dated June 7, 1887.

Application filed February 1, 1887. Serial No. 226,134. (No model.)

To all whom it may concern:

Be it known that I, HORACE E. DOGGETT, of the city and county of Philadelphia, in the State of Pennsylvania, have invented certain new and useful Improvements in Steam-Motors, of which improvements the following is a specification.

The object of my invention is to provide a motor propelled by steam for running sewing-machines and other apparatus, and so constructed and arranged that dead-centers may be overcome, and direct and positive movements of the apparatus actuated thereby always insured.

15 My invention consists in providing within two metallic plates or disks, forming a housing, preferably four cylinders, having chests for admitting steam thereto from a supply connected therewith. These steam-chests in the 20 outer ends of the cylinders are provided with valve mechanism actuated by means of a cam secured to a driving-shaft, and the steam-chests separated from the piston-chambers of the cylinders by a circular plate, having a central 25 opening therein, through which the steam passes in a downward direction when the valve mechanism is automatically raised, permitting of the free movement of the pistons provided with connecting-rods attached to a 30 crank secured to the main driving-shaft of the machine within the housing, and imparting by a direct and positive movement rotary motion to the main driving-shaft of the machine, to which the motor may be readily and quickly 35 applied. The respective cylinders are provided with exhaust-openings connected with a pipe which conducts the exhaust-steam off into any suitable receptacle.

The nature of my invention will be more 40 fully understood when taken in connection with the accompanying drawings, wherein I have shown the same in a form which has been found practically efficient in its application to sewing-machines, and in which—

45 Figure 1 is a perspective view of so much of a sewing-machine as will serve to demonstrate how my improved motor may be applied thereto for operating the same. Fig. 2 is a front elevation thereof with one of the disks 50 removed, showing the cylinders with their

pistons in the different positions therein, and also the steam-supply pipe connected with the respective cylinders. Fig. 3 is a transverse section on the line $z z$ of Fig. 2; and Figs. 4 and 5 are respectively cross-sections on the 55 lines $x x$ and $y y$ of Fig. 2, showing the cylinders and their pistons and connecting-rods attached to a crank secured to the main driving-shaft, and the steam-chests with their valve mechanism automatically actuated by a cam 60 secured to the same shaft.

Referring to the drawings for a further description of my invention, A is the main driving-shaft of the sewing-machine B, to which is rigidly secured a balance-wheel, C, provided 65 with one or more grooves for the reception of a rope or belt for operating a series of machines from one motor, if so desired.

D and D' are two metallic plates or disks, forming a housing, and through the plate or disk D, the main driving shaft A of the sewing-machine revolves, when the motor is actuated in a manner to be presently fully explained.

E is a cam carried on the main driving-shaft A, and E' is a crank rigidly secured to the same shaft.

F, F', F'', and F''' are four cylinders attached to the disk D' and arranged equidistant from each other, with steam-chests G in the outer 80 ends of the respective cylinders, into which steam is admitted through the pipe H from a steam-supply connected therewith in any suitable manner. The steam-chests G are preferably provided with cap-plates i, having 85 flanged rims which are fitted rigidly thereon. Projecting downward through the center of the cap-plates i are openings i' for the reception of the stems of the puppet-valves J, and around which openings are provided suitable 90 packing-rings, i'', and abutting against which are adjustable screws i''' for making steam-tight joints—that is, for preventing the escape of steam from the respective steam-chests G.

Parallel to and in line with the stems of the 95 puppet-valves J are provided rods K, held in guides or bearings k and k', rigidly secured to the disk D. These rods K abut against the cam E, rigidly attached to the main driving-shaft A, and are raised and lowered 100

thereby. The respective stems of the puppet-valves *J* are coupled to the rods *K* by means of cross connecting-bars *L*, having eyes *l* and *l'*, into which set-screws *l²* and *l³* are inserted for rigidly holding the rods *K* and the stems of the puppet-valves *J* in proper position for performing their functions. The cross connecting-bars *L* have attached thereto retracting-springs *M*, having their opposite extremities held by hooks *m*, cast or otherwise secured to the respective cylinders of the motor.

N, *N'*, *N²*, and *N³* are the piston-heads moving freely up and down within the respective cylinders, and to which are pivoted connecting-rods *n*, *n'*, *n²*, and *n³*, held in bearings in the interior surfaces of the respective piston-heads, the opposite extremities of the piston-rods being secured, respectively, to a crank-pin, *n⁴*, attached to the crank *E'*, carried upon the main driving-shaft *A*. In the walls of the respective cylinders *F*, *F'*, *F²*, and *F³*, and extending through the disk *D'*, are provided exit-openings *r* in direct communication with a pipe, *R*, for conducting the exhaust-steam into any suitable receptacle in any well-understood manner.

The mode of operation of the steam-motor hereinabove described may be explained in the following manner: The four cylinders, with their respective pistons, being in the position shown in Fig. 2, steam is admitted from any suitable source through the pipe *H*, and as the steam-chests *G* in the cylinders *F'*, *F²*, and *F³* are closed, the steam will pass, of course, by means of the pipe *H*, through into the steam-chest *G* of the cylinder *F*, which is open, and the puppet-valve *J* will have been raised by means of the cam *E*, aided by the rod *K*, to the position as shown in Fig. 2, and the course of the steam, after its admission into the steam-chest *G* from the pipe *H*, will be in a downward direction into the piston-chamber of the cylinder *F*, actuating the piston *N* and its connecting-rod *n*, thereby operating the crank *E'* (secured to the main driving-shaft) one-fourth of a revolution to the left, by which time the steam-chest *G* of the cylinder *F³* and the puppet-valve *J* thereof will have been raised by the cam *E*, aided by the rod *K*, causing a movement of the piston *N³*. The exhaust-steam from the piston-chambers of the respective cylinders will of course be conducted therefrom by means of the pipe *R* into any suitable receptacle or blow-off, and hence it will be observed that the operation will be continued for the movement of the pistons *N²* and *N'* of the cylinders *F²* and *F'* in regular succession in a similar manner to that above described, thereby actuating the main driving-shaft of the machine; and when desired the motor may be brought to a state of rest by simply turning the steam off by means of a stop-cock connected with the steam-supply pipe *H* in a well-understood manner.

It is obvious that modifications may be

made in details of my invention without departing from the principle or sacrificing the advantages of the invention—for instance, a greater or less number of cylinders may be used, if desired—but I prefer, however, to construct and arrange the parts of the motor in the manner hereinbefore described.

Having thus described the nature and objects of my invention, what I claim as new, and desire to secure by Letters Patent, is—

1. The combination, with two metallic plates, a shaft, and a cam secured to said shaft, of three or more cylinders provided with steam-chests and piston-chambers, a supply-pipe communicating with said steam-chests, and an exhaust-pipe connected with said piston-chambers, puppet-valves provided in said steam-chests, and means operated by said cam for raising and lowering said valves, a crank secured to said shaft, and pistons with their connecting-rods attached to said crank, substantially as and for the purposes set forth.

2. The combination, with two disks and the driving-shaft of a machine, of four cylinders provided with steam-chests and piston-chambers separated from each other by a plate having a central opening therein, puppet-valves provided in said steam-chests, a cam secured to said shaft, and means, substantially as described, operated thereby for actuating said valves, steam supply and exhaust pipes in direct communication with said cylinders, and a crank secured to said shaft and pistons with their connecting-rods attached to said crank, substantially as and for the purposes set forth.

3. The combination, with two disks, a shaft having a bearing in one of said disks, and a cam secured to said shaft, of a rod, *K*, held in bearings secured to one of said disks, a cross-bar suitably attached thereto, a cylinder having a steam-chest and a piston-chamber, a puppet-valve, the stem of which is secured to said cross-bar and actuated by said cam, and a spring attached to said cross-bar and cylinder, substantially as and for the purposes set forth.

4. In a steam-motor, the combination, with a cylinder having a removable cap-plate, a packing-ring in said plate, an adjustable screw abutting against said ring, and a puppet-valve playing freely up and down through said plate and screw, of a main driving-shaft, and two metallic disks forming a housing for said cylinder, a cam secured to said shaft, a rod, *K*, held in bearings in one of said disks, a cross-bar secured to said rod and to the stem of said puppet-valve, and a helical spring attached to said cross-bar and cylinder, all arranged substantially as and for the purposes set forth.

In witness whereof I have hereunto set my hand in the presence of two subscribing witnesses.

HORACE E. DOGGETT.
